(57) **CLAIM**

I claim the ornamental design for a wheel rim, as shown and described.

DESCRIPTION

FIG. 1 is a front elevation view of a wheel rim embodying the new design;

FIG. 2 is a top, front, and right-side perspective view thereof; and,

FIG. 3, is a cross-sectional view thereof.

The broken lines depicting portions of the wheel rim form no part of the claim.

The hatching lines viewed in FIG. 3 are for illustrating inside portions of the wheel rim and form no part of the claimed design.
